Application March 16, 1937, Serial No. 131,206

6 Claims. (Cl. 303—21)

This invention relates to railway vehicles and particularly to the braking thereof.

It is an object of this invention to provide, for railway vehicles, braking means adapted to achieve, when applied, the ultimate efficiency of deceleration, while preventing slippage or loss of traction between the vehicle wheels and the supporting tracks, and while achieving the utmost smoothness of operation.

10 It is a further object of this invention to provide means responsive to the speed of a railway vehicle for controlling the intensity of wheel brake application thereon.

It is a further object of this invention to provide means responsive to the speed of a moving railway vehicle to control the intensity of application of the track brakes thereof.

It is a further object of this invention to provide means responsive to the speed of a moving railway vehicle to simultaneously control the intensity of application of the wheel and track brakes at a rate proportional to the co-efficient of braking friction which is dependent upon the speed of the moving vehicle.

25 It is a further object of this invention to provide such means whereby the downward force applied by the track brakes of a vehicle downwardly upon the axles of the truck thereof will increase the traction between the moving vehicle wheels and the supporting rails to reduce slippage and loss of traction therebetween.

It is a further object of this invention to provide such means which may be applied with facility and with minimum expense to railway vehicles provided with conventional air brake systems without the necessity for substantial modification of the conventional braking systems thereof.

40 It is a further object of this invention to provide, in such means, a common means associated with an axle of a railway vehicle to control the intensity of wheel and track brake applications at a rate proportional to the speed of the vehicle and proportional also to the co-efficient of braking friction which is proportional to the vehicle speed.

These and other objects and advantages will appear from the following description taken in connection with the drawings.

50 In the drawings:

Figure 1 is a diagrammatic view, showing the application of the principles of our invention to the automatic braking system and an axle of a railway vehicle;

55 Figure 2 is an enlarged elevational view, in

section, of the electromagnetic valve device illustrated in Figure 1;

Figure 3 is an elevational view, partly in section, of the axle speed responsive biasing rheostat shown in Figure 1;

Figure 4 is a diagrammatic view illustrating the arrangement of the resistance elements of the biasing rheostat illustrated in Figure 3, with respect to the armature thereof;

Figure 5 is a fragmentary diagrammatic view, 10 illustrating the application of the principles of this invention, with track brakes having fluid engine positioning means; and

Figure 6 is a similar view illustrating the application of the principles of this invention with 15 track brakes applied through energization of a solenoid connected in the track brake shoe energizing circuit.

The high speed of operation of new and modern main line rail equipment requires, in the braking of the vehicles, the application of the maximum allowable pressure to the wheels by the wheel brakes. It is desirable that the pressure of application of the wheel brakes be controlled and retained, at all times, at the maximum limit so that the train or vehicle may be stopped in the shortest possible distance, with the utmost smoothness and the achievement of the maximum braking effect and ultimate comfort to railway passengers.

30 The determining factor in the application of the wheel brakes is the adhesion or traction between the vehicle wheels and the supporting rails. All braking effect exerted upon a railway vehicle by the wheel brakes is dependent upon the traction between the wheels and the supporting rails. Since the co-efficient of friction between rubbing parts varies with the speed, the co-efficient of friction between the brake shoes and the treads of the vehicle wheels increases as the speed of 40 the vehicle decreases.

The use of magnetic track brakes enables us to materially increase the efficiency of braking and to bring to a stop, in the shortest possible distance, a vehicle equipped both with wheel brakes and with track brakes. The track brakes, in addition to applying a braking force which is additive to the braking force applied by the wheel brakes, also exerts a downward force on the wheels of the vehicle to which they are applied 45 in order to force the vehicle wheels against the rails and increase the adhesion or traction between the wheels and the rails.

50 While the efficiency of wheel brakes is materially impaired by unfavorable track conditions, 55

such as sleet, snow, ice and rain which materially decrease the traction of the wheels thereon, it is found that the track brakes are relatively unaffected by such unfavorable track conditions and that they decrease the effect of such conditions on the wheel brakes by increasing the traction between the wheels and the track rails. In addition, the track brakes may be safely applied at all times at their maximum intensity, and it is our purpose, in controlling the intensity of application thereof, only to produce smoothness in stopping and comfort to the passengers of the railway vehicles.

Where, due to unfavorable track conditions, the traction or adhesion between wheel and rail is reduced, upon application of the wheel brakes at too great intensity manually, by the operator, or by other means, the wheels will be locked and will slide upon the rail, thereby destroying all 15 braking efficiency of the brakes. This undesirable condition most often arises during manual application of the wheel brakes, where the human element controls the rate of brake application. It is the principal object of this invention to 20 overcome this dangerous and undesirable occurrence by eliminating the human element as a controlling factor in brake application in order to secure the maximum possible braking efficiency at all times by controlling the intensity of wheel 25 brake application by traction or adhesion between rail and wheel regardless of track conditions in order to secure the maximum obtainable retardation with a given track condition and a given co-efficient of braking friction or value of 30 traction or adhesion between wheel and rail. In the practice of our invention, the maximum retardation obtainable is secured for each given speed during application of the wheel brakes.

There is no fixed rate of retardation, and there 35 is no predetermined fixed rate dependent upon the judgment of the human operator. This invention, in operation, does not hinder or interfere with brake application, but governs the brake shoe pressure in proportion to the then existing 40 co-efficient of traction or adhesion between wheel and rail for the speed at which the train or vehicle is traveling. The fluid pressure in the brake cylinder is diminished or reduced as the speed is 45 reduced and in proportion to the increase of co-efficient of friction between the brake shoe and 50 wheel.

Referring to the drawings in detail and with reference particularly to Figure 1, the conventional brake pipe 1 is connected by the pipe 2 to the 55 brake valve 3 which is provided with an inlet 4, connected to any suitable source of fluid pressure, and the outlet 5. The valve 3 may be manually operated to connect the pipe 2 to the pipe 4 in order to build up a pressure in the 60 brake pipe or to the outlet 5 to reduce the pressure in the brake pipe. The brake pipe 1 is provided at each end with conventional angle cocks 1a and flexible hose connections 1b.

Connected in the brake pipe 1 is the branch 65 pipe T 6 having connected thereto the pipe 7 which is also connected to the cutout cock 8. The cutout cock 8 is connected by the pipe 9 to the centrifugal dirt collector 10. The dirt collector 10 is connected by the pipe 11 to the triple valve 70 12. The triple valve is conventional and is connected in known manner by the pipe 13 to the reservoir 14 and by the pipe 15 to the electromagnetic valve device 16, which electromagnetic valve device 16 is connected to the fluid cylinder 75 17 which operates the conventional wheel brakes.

A T 18 is provided in the pipe 15, to which is connected the pipe 19 which leads to the upper end of the cylinder of the pressure responsive switch 20. The pressure responsive switch 20 is in the form of an air engine having a cylinder 21 with a piston 22 slidably therein and adapted to be urged downwardly therein against pressure of the spring 23 by fluid pressure in the cylinder 21 above the piston 22.

Rigidly secured to the piston 22 is the stem 10 member 24 having a suitable switch plate 25 rigidly secured to the end thereof. The switch plate 25 of the pressure responsive switch is adapted to engage switch contacts 26 and 27 when the force of the spring 23 is overbalanced 15 by pressure in the cylinder 21 above the piston 22. When the force exerted by the fluid pressure is less than the force of the spring 23, the switch plate 25 is disengaged from the switch contacts 26 and 27.

Contact 26 is connected by means of wire 31 with the coil 29 of the track brake shoe 30. The other terminal of the coil 29 is connected to the ground 28. Contact 27 is connected by wire 33 to the contactor bar 101b which cooperates 25 with the contact plates 101a of the rotor 101 of rheostat 34. The wire 32 is connected from brush 103 of rheostat 34 to the wire 41 which is connected to one terminal of the relief valve 42. The other terminals of the windings of the valves 30 40 and 42 are connected by the cross wire 43, which cross wire 43 is connected by the wire 44 to the ground 45. The rheostat 34 is connected through tapped resistance 104 and resistor 105 to the positive terminal of the source of power 35 35, the negative terminal of which is connected by the wire 36 to the ground 37.

When pressure is introduced into the cylinder 21 to urge the piston 22 downwardly therein and engage the switch plate 25 with the contacts 26 and 27, the brake coil energizing circuit is completed. The brake coil energizing circuit extends from the positive side of the source of power 35 through tapped resistance 104 and bar 101b of rheostat 34, wire 33, contact 27, switch 45 plate 25, contact 26, wire 31, coil 29, to ground 28, and from ground 37 through wire 36 to the negative side of the source of power 35. The valve winding energizing circuit extends from the positive side of the source of power 35, 50 through tapped resistance 104, commutator resistance 102c and brush 103 of rheostat 34, wire 32, to the wires 39 and 41, and thence cross wire 43, and wire 44 to the ground 45 and from ground 37 to wire 36 to the negative side of the source 55 of power 35. Thus, upon operation of the triple valve 12 to connect the reservoir 14 with the pipe 15, the switch plate 25 is brought into engagement with the contacts 26 and 27 to complete the energizing circuit for the coil 29. The intensity 60 of energization of the windings and the coil depends upon the amount of resistance inserted between the source of power 35 and the wires 32 and 33 by the rheostat 34. The amount of resistance inserted between the source of power 65 35 and the wires 32 and 33 is proportional to the speed of the vehicle axle due to the control of the rheostat 34 by the centrifugal rheostat control mechanism, the structure and operation of which will be hereinafter more clearly described.

The details of the electromagnetic valve device are illustrated in Figure 2. The inlet valve 46 is provided with a housing 48 having a cap plate 47 rigidly secured to the upper end thereof by 75

means of screw bolts 48. The housing 46 is provided at its upper end with a suitable supporting chamber in which is disposed the winding 49 which is suitably insulated from the metallic housing 46 and cap plate 47. The inner side of the cap plate 47 is provided with a projection 47a which is surrounded by one end of the compression spring 50. The lower end of the compression spring 50 abuts the armature 51 which has at its upper end a projection 51a which extends within the lower end of the compression spring 50. A similar projection 51a is disposed at the bottom end of the armature 51 and extends into the upper end of the compression spring 52 which is in abutment with the armature 51. The compression spring 52 extends into the upwardly extending cylindrical portion of the cup-shaped spring shoe 53 which is slidable in the housing 46 and which rests upon the diaphragm 54 which is secured between the lower end of the housing 46 and the extension 56 of the casting 57. The housing 46 is screw-threadedly attached to the extension 56.

The casting 57 which is cylindrical is provided with an extension 58 disposed oppositely and in alignment with the extension 56, and also an extension 58 which is axially spaced from the extension 56. The cylindrical casting 57 is provided with a wall 60, which divides the cylindrical portion thereof into two chambers, namely, the inlet chamber 61 and the pressure chamber 62. This wall is provided with a horizontal port 63 having a valve seat upon which rests the valve member 64. This valve member 64 is connected by the stem 65 with the piston 66 which reciprocates in the cylinder 67 provided in the extension 58. The lower end of this cylinder 67 is closed by the cap 68 which is screw-threadedly attached to the extension 58. The cylinder 67 communicates with the pressure chamber 62 through the passage 69 in the top wall 70 of the cylinder 67, which is provided with a central boss in which the stem 65 is slidably supported.

Screw-threadedly secured in the upper portion of the wall 60 is the valve supporting member 71 which is provided, at its upper end adjacent the diaphragm 54, with a cylindrical chamber 72. The lower end of the member 71 is provided with a seat 73 which is adapted to cooperate with the valve member 74 which is secured by the stem 75 to a nut member 76 which is disposed in the chamber 72 and normally urged upwardly therein by the spring 77 which has the upper end thereof in engagement with the nut member 76 and the lower end thereof in engagement with the lower wall of the chamber 72. A suitable aperture is provided in the member 71 between the chamber 72 and the seat 73 to slidably support the stem 75. A pressure chamber 78 is also provided in the member 71 above the seat 73 and this chamber is connected by the passage 79 to the lower end of the cylinder 67 below the piston 66. Surrounding the upper end of the member 71, which is provided with the chamber 72, is the auxiliary pressure chamber 80 which is connected by the passage 81 to the pressure chamber 62.

The inlet valve 40 operates as follows: When the resistance inserted in the energizing circuit of the valve 40 is of maximum ohmic value, the position of the parts of the valve 40 is shown in Figure 2. Due to the minimum intensity of energization of the winding 49, the downward force applied by the armature 51 to spring 52 is of minimum value. The spring shoe 53 is applied with minimum force to the diaphragm 54 to unseat the

valve member 74 and permit pressure from the inlet chamber 61 to pass through the chamber 78 and passage 79 to the lower part of cylinder 67 below the piston 66. The valve member 64 will be unseated and fluid under pressure will pass from the inlet chamber 61 through port 63 to the pressure chamber 62. This pressure in the pressure chamber 62 will be transmitted through passage 81 to auxiliary pressure chamber 80 and thus applied to the diaphragm 54.

When the pressure in the pressure chamber 62 and the proportional pressure in auxiliary pressure chamber 80 is sufficient to overcome the downward force applied to the spring shoe 53, the diaphragm 54 is thrust upwardly to permit the spring 77 to seat the valve member 74 and shut off the pressure applied in cylinder 67 below the piston 66. The valve member 64 will then be closed. As the pressure applied downwardly by the spring shoe 53 varies directly with the intensity of energization of the winding 49, the necessary pressure built up in the auxiliary pressure chamber 80 to cause seating of the valve member 64 will vary directly with the intensity of energization of the winding 49. The intensity of energization of the winding 49 will, therefore, control the fluid pressure which passes from the inlet chamber 61 to the pressure chamber 62. When the intensity of energization of the winding 49 is increased by reduction of resistance between the source of power 35 and the wire 33, the pressure necessary to be built up in the pressure chamber 62 to close valve member 64 will be proportionally reduced. The reason for maximum energization of the solenoid 49 at slow speed and subsequent weakening thereof as the speed is increased is to overcome any danger of cutting off the air supply to cylinder 67 should the solenoid energizing circuits be damaged.

The release valve 42 is provided with a housing 83 which is screw-threadedly attached to the extension 59. The upper end of the housing 83 is closed by a cap plate 84 similar to the cap plate 47 and having a central projection 84a similar to the projection 47a. The cap plate 84 is secured to the housing 83 by the bolts 85. The upper portion of the housing 83 is provided with a chamber which contains the winding 86 which is similar to the winding 49 and which is insulated from the housing 83 in the same manner as the winding 49 is insulated from the housing 46. Disposed in the housing 83 and cooperating with the winding 86 is the armature 87 which is similar to the armature 51 and which is biased downwardly by the compression spring 88 similar to the compression spring 50, which has its upper end surrounding the projection 84a and its lower end surrounding the projection 81a on the armature 87.

Below the armature 87 and having its upper end in engagement with the armature 87 is the compression spring 89 which has its lower end in engagement with a suitable groove in the thrust plate 90. The thrust plate 90 is secured by means of the nut 91 to the reduced upper end of the valve stem 93 which has the valve member 92 integral with the lower end thereof. The housing 83 is provided with a horizontal lower wall 94 having a central boss provided with a suitable aperture for slidably supporting the valve stem 93. The lower wall 94 is also provided with a passage 95 which leads from the lower side thereof radially outwardly to the atmosphere. The extension 59 is provided with a lower reduced bore 96 having a valve seat 97

at its upper end for cooperation with the valve member 92.

Above the valve seat 87, the extension 88 is provided with an enlarged bore which cooperates with the wall 84 of the housing 83 to form the exhaust chamber 88 having constant communication, through the passage 85, with the atmosphere. The springs 86 and 88 and the armature 87 apply downward force to the thrust plate 89 in the same manner as the compression springs 80 and 82 and armature 81 apply downward force to the spring shoe 83 of the valve 48. The downward force applied varies directly with the intensity of energization of the winding 86. Therefore, the pressure retained in the pressure chamber 82 by the valve member 82 is also proportional to the intensity of energization of the winding 86. The intensity of energization of the winding 86 varies inversely with the amount of resistance inserted between the source of power 35 and wire 22 by rheostat 34. The pressure chamber 82 communicates directly with the wheel brake cylinder 17 and, therefore, the pressure in the chamber 82 and in the cylinder 17 is equal. When the winding 86 is de-energized, and when the pressure in the chamber 82 and cylinder 17 is sufficient to unseat the valve member 82, fluid escapes through exhaust chamber 88 and passage 85 to the atmosphere.

As will hereinafter more clearly appear, the amount of resistance inserted in the energizing circuits by the rheostat 34 varies directly with the speed of the vehicle. If, while the vehicle is traveling at high speed, pressure is reduced in the brake pipe 1 to cause operation of the triple valve 12 to connect the reservoir 14 with the pipe 15, the brake coil energizing circuit is completed by the pressure responsive switch 20 to energize the track brake coil at an intensity which is governed by the speed controlling governor. As the vehicle decelerates, the speed responsive rheostat 34 progressively cuts out resistance in the valve energizing circuits to strengthen the solenoids of the valve device 18. The strengthening of the intensity of energization of the winding 86 reduces the downward force applied to the valve member 82 and, where the pressure in the chamber 82 is sufficient, the valve member 82 will be unseated and the pressure exhausted until the pressure in the pressure chamber 82 and the brake cylinder 17 is reduced to a value proportional to the intensity of energization of the winding 86. The speed of the vehicle at the time of initial application determines the intensity of energization of the winding 49 of the valve member 48 and, therefore, determines the amount of fluid pressure initially admitted through the valve 48 to the pressure chamber 82 and the brake cylinder 17 which is in direct communication therewith.

The rheostat 34 comprises the casing 33 having rotatably mounted therein the rotor shaft 100. The rotor shaft 100 has rigidly secured thereto the rheostat rotor 101, to which is rigidly secured the armature 102. The rheostat rotor 101 is provided with a plurality of contact plates 101a suitably insulated from one another and each adapted to have progressively connected thereto a tap of a tapped resistance element 104. The end tap of the resistance element 104 is connected by wire 102b to the armature resistance 102c which has each of its respective taps connected to an armature plate 102a of the armature 102.

75. Secured in known manner in the casing 22 is

the main brush 103 and contactor bar 101b which are resiliently urged into contact with the armature 102 and rotor 101 respectively. Each of the contact plates 101a of the rotor 101 is adapted to be progressively engaged by a collector brush 104a, and the respective collector brushes 104a are each connected to a tap of the resistance element 104 which is connected through resistor 105 to the positive terminal of the source of power 35. When the rotor shaft 100 is revolved, as indicated by the arrow in Figure 4, the brush 103 successively contacts various of the plates 102a of the armature 102. Various resistance values are thereby inserted between the wire 32 and the source of power 35 in order to weaken or strengthen the valve energizing circuits as described above. The armature 102 is preferably so arranged with respect to the brush 103 that, when the speed of the vehicle is zero, the minimum resistance value is inserted between the wire 32 and the source of power 35. Upon increase of the vehicle speed, the shaft 100 is caused to rotate by operation of the governor mechanism to revolve the shaft 100 in the direction indicated by the arrow in Figure 4 to progressively increase the resistance value inserted between wire 32 and source of power 35, whereby to so control the valve energizing circuits that the intensity of energization of the valves 40 and 42 is proportional to the speed of the vehicle. Upon cessation of the vehicle, the brush 103 is urged into contact with the contact bar 101b.

Upon rotation of the shaft 100, as described above, the proportion of the resistance element 104 inserted between source of power 35 and contactor bar 101b is decreased and the intensity of energization of the brake coil 28 is thereby varied directly with the speed of the vehicle. 35

For the purpose of balancing the circuits of the various vehicles in a train, a fixed resistance 105 is inserted between the collector brushes 104 and the source of power 35. The value of this resistance may be changed for the purpose of balancing the respective circuits and for changing the operating characteristics of the respective control mechanisms. The arrangement of the brush 103, contactor bar 101b, the plates 102a and resistance 102c of the armature 102 and the collector brushes 104a are diagrammatically illustrated in Figure 4, which also shows the manner in which the resistance element 105 is inserted in series with the source of power 35 between the source of power and the rheostat 40 45 50 55

The construction of the speed responsive governor for controlling the rheostat 34 is shown in Figure 3 and comprises the main casting 106 having the base casting 107 rigidly secured thereto by means of bolts 108, which extend through abutting flanges thereof. Each of the castings 106 and 107 is provided with oppositely disposed semi-circular bearing members at opposite sides which are adapted to form an annular bearing for surrounding the axle 110 which is rotatable therein and which supports the main casting 106 and associated parts. The main casting 106 is provided with a recessed bearing boss 109 which rotatably supports the inner end of the rotor shaft 108 which has its outer end supported in a suitable bearing provided in the casing 33 of the rheostat 34. At its upper end, the main casting 106 is provided with a bowl-shaped governor housing portion 111 having thereon an ear 112 which is pivotally attached to the lower end of a bifurcated bracket arm 113 which is adapted to have its other end suitably secured to the base casting 107.

ably pivotally attached to the truck or frame of a railway vehicle.

Suitably secured to the top of the governor housing 111 is the cap plate 114 which is provided with central thrust bearing means for supporting the rotor shaft 115 which is provided at its lower end with a pinion 116 which is rigidly secured thereto. The pinion 116 is adapted to mesh with a gear 117, which is a split gear comprising halves clampingly secured to the axle 110 by means of bolts or other suitable means. By means of this connection, rotation of the axle 110 is translated into rotation of the governor shaft 115 in either direction at a speed proportional to the speed of rotation of the axle 110 and, necessarily, to the speed of the vehicle when perfect traction exists between wheels and track rails. Rotor shaft 100 is provided with a gear 118 which is rigidly secured thereto and which engages a rack 120 on the sleeve 119 which is axially slideable on the shaft 115.

At its upper end, the sleeve 119 is provided with an annular flange which is rigidly secured within the thrust collar 121 which comprises complementary members bolted or otherwise rigidly secured together, the top member of which is provided with oppositely disposed ears 122, each having the lower end of a link 123 pivotally attached thereto. The upper end of each link 123 is pivotally secured to a weight lever 124. The weight levers 124 are provided with weight members 125 at the outer ends and have their inner and upper ends pivotally secured to ears 126 on the shaft 115. By means of this structure, the thrust collar 121 and the sleeve 119 will move upwardly, upon rotation of the axle 110, a distance proportional to the speed of the axle 110. The rotor shaft 100 will be rotated through an arc proportional to the speed of the axle 110 because of the engagement of the gear 118 with the rack 120 on the sleeve 119. Therefore, by means of this structure, the resistances inserted by the rheostat 34 between the source of power 35 and the wires 32 and 33 are proportional to the speed of the vehicle.

Due to the fact that, upon application of the brakes of a railway vehicle, the weight will be distributed on the axles of the vehicle in such manner that the weight on the forward axles is increased and the weight on the rear axles is decreased, it is preferred that the rheostat 34 and the controlling governor mechanism be mounted on the rearmost axle of the car. The advantage of this disposition of the rheostat and controlling governor is that the governor mechanism is made responsive to the speed of the rearmost axle, the wheels 110a of which will be most likely to slide on the rail due to loss of traction between the wheels and the rails. The rearmost wheel brakes will, therefore, be most likely to be locked and the speed of the rearmost axle be the most likely to be brought first to zero. Therefore, upon the locking of the brakes on the wheels of the rear axle, the rheostat 34 will insert the correct resistance between the wires 32 and 33 and the source of power 35, whereby to cause the strengthening of the energizing circuits and necessarily decrease the air pressure in the air brake cylinder 17 by stopping the flow of fluid pressure through valve 40 and exhausting sufficient fluid pressure to permit the wheels to unlock and begin turning.

While Figure 1 illustrates the application of the principles of our invention to a vehicle equipped with conventional track brakes which

are applied solely by energization of the coil 29 thereof, it is, of course, to be understood that our invention is susceptible of application to vehicles unequipped with track brakes, in which case the wires 31 and 33, the pressure responsive switch 20, the pipe 19 and the track brakes will be omitted.

Furthermore, the control means may be connected to the track brake circuit alone, the electromagnetic valve device 16 and wire 32 being omitted by connecting the pipe 15 directly to the cylinder 17, as is conventional practice.

It is also contemplated by us that the principles of our invention may be applied to a vehicle equipped with track brakes which are applied by energization of a solenoid connected in the track brake energizing circuit, as illustrated in Figure 6. A form of this type of brake is illustrated in United States Letters Patent No. 1,724,266 granted August 13, 1929, to T. Elliott.

As shown in Figure 6, the solenoid 127 is connected in the energizing circuit of the coil 29 and is energized simultaneously therewith and the intensity of energization of the solenoid 127 is proportional to the intensity of energization of the coil 29. The brake shoe 30 is supported by springs 128 at such distance from the rail that the rail is spaced from the magnetic field thereof. Cooperating with the solenoid 127 is the armature 129 which is pivotally attached to the intermediate portion of the lever 130 which has one end suitably pivotally supported on the railway vehicle and the other end thereof provided with a projection which engages the top of the track brake shoe 30. Upon energization of the solenoid 127, the lever 130 is drawn downwardly to move the shoe 30 downwardly against the upward force of the springs 128 so that the rail will be disposed within the magnetic field of the energized shoe. This causes application of the shoe 30 to the rail. The necessary modification of the circuit and the structure shown in Figure 1 is illustrated in Figure 6.

It is further contemplated that the principles of this invention may be applied to railway vehicles equipped with track brakes which are positioned, by fluid pressure, sufficiently close to the rail to permit energization of the shoe 30 to cause application thereof to the rail. Such structure is illustrated in Figure 5 and comprises the air engine 131 which has a cylinder 132, in which is slidably disposed a piston 133 which is urged upwardly by the compression spring 134. The piston 133 is connected by the stem 135 to the top of the track brake shoe 30. The upper end of the cylinder 132 is connected by pipe 136 to the pressure chamber 62 of the electromagnetic valve device 16. The track brake shoe 30 is thus normally supported by the spring 134 at substantial distance from the rail. When, however, fluid pressure builds up in the pressure chamber 62, this fluid pressure is transmitted through pipe 136 to the upper end of the cylinder 132 above the piston 133. When sufficient fluid pressure is built up above the piston 133, the stem 135 will be thrust downwardly at a rate proportional to the pressure in the cylinder 132, whereby to position the brake shoe sufficiently closely adjacent the rail to place the rail within the magnetic field of the energized track brake shoe.

The speed of application is, therefore, proportional to the pressure supplied to the cylinder 132 from the pressure chamber 62 of the electromagnetic valve device 16. The speed of application for a given fluid pressure may be varied by

varying the strength of the compression spring 134. The time required for application of the shoe 38 to the rail may be varied by varying the length of the stem 135 or the distance of the fluid engine 131 from the rail. The intensity of application of the shoe to the rail will also be proportional to the fluid pressure in the cylinder 132, because the upward force of the spring acts in opposition to the downward force exerted by the fluid pressure and weight of the brake shoe.

Operation

In the operation of the above-described mechanism, the pressure in the brake pipe 1 is reduced in known manner and the triple valve 12 operates to connect the pipe 13 with the pipe 15, whereby to transmit the fluid pressure from the reservoir 14 to the pressure responsive switch 20. Upon operation of the pressure responsive switch 20, the switch plate 25 engages the contacts 26 and 27 to complete the energizing circuit of the track brake coil 29. The intensity of energization of the windings of the valves 40 and 42 and of the coil 29 of the track brake shoe will be proportional to the speed of the vehicle at the time the application is initiated because the amount of resistance between the source of power 35 and the wire 33 is always proportional to the speed of the axle 110. The pressure admitted to the pressure chamber 62 will likewise be proportional to the speed of the axle 110.

If the vehicle is traveling at high speeds, relatively little resistance will be inserted by the rheostat 34 between the source of power 35 and wire 33 and, therefore, the intensity of energization of the brake coil 29 will be substantially great, likewise the amount of resistance in circuit with wire 32 to the valve device 16 will be high and the fluid pressure supplied to the cylinder 17 will, likewise, be substantially great. Therefore, as energization of the coil 29 of the track brake shoe takes place simultaneously with operation of switch 20, simultaneous application of the wheel brakes and the track brake will be produced.

As the speed of the vehicle is reduced, added resistance is progressively inserted between the source of power 35 and wire 33 by the rheostat 34. This decreases the intensity of energization of the track brake coil and likewise, as the speed is reduced, resistance is progressively cut out between the source of power 35 and wire 32 by the rheostat 34 to increase the intensity of energization of the valve windings 40 and 42, the pressure in the pressure chamber 62 of the magnetic valve device 16 is reduced to reduce the pressure of wheel brake application while the intensity of track brake application is simultaneously and proportionally reduced by reduction of intensity of energization of the coil 29 of the track brake shoe 38.

Where the track brake is omitted, the operation is similar, save that the only function performed by the rheostat 34 is to control the intensity of energization of the windings of valves 40 and 42.

Where the type of brake utilized is that illustrated in Figure 6, the operation is as described above, the only difference being that the solenoid 127 is energized to an intensity proportional to the intensity of energization of the coil 29, whereby downward force applied by the lever 130 to the brake shoe 38 is likewise controlled.

75 Where the structure is as illustrated in Figure 5,

the fluid pressure supplied to the cylinder 132 above the piston 133 is proportional to the pressure in the pressure chamber 62 of the magnetic valve device 16 and, as this pressure is controlled, as described above, by controlling the energization of the windings of valves 40 and 42, the fluid pressure above the piston 133 in the cylinder 132 is likewise controlled. As the speed of the vehicle decreases, added resistance is progressively inserted by the rheostat 34 in the respective energizing circuits whereby to reduce the intensity of energization of valves 40 and 42 along with the coil 29 of the track brake. As the intensity of energization of the windings of valves 40 and 42 is decreased, the pressure in the pressure chamber 62 of the valve device 16 is progressively reduced, whereby to progressively reduce the fluid pressure in the wheel brake cylinder 17; and, in the case of Figure 5, also the pressure in the air engine 131. When the pressure in the air engine 131 is thus reduced to a point where the force of the spring 134 is sufficient to overcome the force of the coil 29, the intensity of which energization has been reduced, as explained above, the track brake will be released from the rail; and likewise, when the pressure in cylinder 17 is sufficiently reduced, the wheel brakes will be released.

It will thus be seen that the intensity of initial application is proportional to the speed of the vehicle and that the intensity of both wheel and track brake application is progressively reduced as the speed of the vehicle decreases to zero and as the co-efficient of braking friction increases. The ultimate braking efficiency is thus achieved automatically without reliance upon human discretion, the controlling factor of the above operation being the speed of rotation of the rearmost axle which, due to the above described occurrence of weight re-distribution upon brake application, is most sensitive to loss of traction between the wheels thereof and the supporting track rails. The human element is thus totally abolished and the track brakes, in addition to producing a retardation which is additive to that produced by the wheel brakes, also increases the efficiency of the wheel brakes by exerting downward force upon the vehicle to increase traction between the wheels and the supporting rails or to decrease slippage between the wheels and the supporting track rails.

It is, of course, to be understood that, by suitable adjustment of various of the above-described mechanisms, the operating characteristics may be widely varied.

It is further to be understood that the principles of this invention may be applied to vehicles of various constructions having braking systems of various types other than that herein illustrated and described above.

The term "intensity of brake application" is herein used to designate force of brake application.

It is likewise to be understood that the above-described structure is merely illustrative of the manner in which the principles of our invention may be utilized and that we desire to comprehend within our invention such modifications as come within the scope of the claims and the invention.

Having thus fully described our invention, what we claim as new and desire to secure by Letters Patent is:

1. In brake control mechanism for a rail vehicle having wheel brakes and track brakes, com-

mon means for causing application of said wheel brakes and said track brakes, and means responsive to the speed of the vehicle for constantly maintaining the intensity of application of said brakes proportional to the speed of said vehicle during brake application, said last-named means including a biasing rheostat and a centrifugal governor device operatively connected to an axle of the vehicle.

5 10 2. In brake control mechanism for a rail vehicle having wheel brakes and track brakes, common means for causing application of said wheel brakes and said track brakes, and means responsive to the speed of the vehicle for constantly 15 maintaining the intensity of application of said brakes proportional to the speed of said vehicle during brake application, said last-named means including a biasing rheostat and a centrifugal governor device operatively connected to the rearmost axle of the vehicle.

15 20 3. In brake control mechanism for a railway vehicle having wheel brakes, means including a fluid cylinder for applying said wheel brakes, and an electromagnetic track brake; means for maintaining the intensity of initial application of said 25 brakes proportional to vehicle speed comprising electromagnetic valve means for controlling the admission of fluid pressure to said cylinder, a common circuit for energizing said valve means and said track brake, and means including a rheostat in said circuit responsive to the speed of a vehicle axle for maintaining the intensity of energization of said valve means and said track 30 brake proportional to the speed of the vehicle.

30 35 4. In brake control mechanism for a railway vehicle having wheel brakes, means including a fluid cylinder for applying said wheel brakes, and an electromagnetic track brake adapted to be applied by energization thereof; means for constantly maintaining the intensity of application of said brakes proportional to vehicle speed dur-

ing deceleration of said vehicle comprising electromagnetic valve means for controlling the admission of fluid pressure to said cylinder, a common circuit for energizing said valve means and said track brake, and means including a rheostat 5 in said circuit and a centrifugal governor device connected to a vehicle axle for controlling said rheostat whereby to maintain the intensity of energization of said valve means and said track brake proportional to the speed of the vehicle 10 during deceleration.

5 15 5. In brake control means for a vehicle having axles, wheel brakes, and track brakes; common means for applying said wheel brakes and said track brakes, and common means for determining the intensity of initial application of said wheel and track brakes, said last-named means including an electromagnetic valve device for controlling the intensity of application of said wheel brakes, a common circuit for energizing 20 said valve device and said track brake, a rheostat in said circuit, and a centrifugal governor mechanism operatively associated with one of said axles and with said rheostat.

6 25 6. In wheel brake control means for a vehicle having axles, wheel brakes, and track brakes; common means for applying said wheel brakes and said track brakes, common means for determining the intensity of initial application of said wheel and track brakes and for maintaining the 30 intensity of application of said brakes proportional to vehicle speed during deceleration of said vehicle, said last-named means including a common circuit for controlling the intensity of application of said brakes, a rheostat in said circuit, and centrifugal governor means operatively 35 connected to one of the vehicle axles and to said rheostat.
